METHOD AND MEANS FOR WINDING COILS

Clifford A. Miller, Cleveland, Ohio

Application May 3, 1946, Serial No. 667,165

20 Claims. (Cl. 140—92.2)

1

My invention relates to the winding of wire coils, such as employed in electric motors, and comprises a novel method and novel apparatus for winding such coils.

My invention has particular application to field coils for electric motors. Such field coils of the type to which my invention relates commonly comprise units or sets of coils, each unit or set comprising a pair of coils of opposite polarity electrically connected together, each coil consisting of an inner and outer coil winding, both windings electrically connected together and positioned face to face, and the windings of one coil of each pair running in one direction and the windings of the other coil of each pair running in an opposite direction.

It has been heretofore known in the art to provide field coils of the general type referred to and with the two windings of each coil both formed of a single piece of wire. It has been customary, heretofore, however, to wind the two coils of each unit or set separately and then connect them together, as by means of soldering the ends of the two coils of the unit or pair together for the electrical connection thereof as a unit consisting of a pair of coils of opposite polarity. It has also been proposed to wind such coil units by hand from a single continuous length of wire.

Obviously, the soldering or other mechanical connection of the ends of the two coils of a pair or set, or the hand winding of the unit, is a tedious and time-taking operation requiring considerable skill and adding materially to the cost of producing field coils of the type referred to.

An important object of the invention has been to provide a machine for winding a coil unit of the type referred to from a single continuous length of wire.

Another object of the invention, therefore, has been to eliminate the necessity for soldering or other mechanical connection of the two coils of the unit of the type referred to.

Another object of the invention has been to develop a method for producing a coil unit of the type referred to, whereby both coils of each unit and both windings of each coil are all simultaneously wound from a single continuous length of wire in a very rapid and expeditious manner.

Another object of the invention has been to provide apparatus or means for winding a coil unit of the type referred to, whereby both coils of the unit and both windings of each coil are all simultaneously wound from a single continuous length of wire in a very rapid and expeditious manner.

2

Another object of the invention has been to provide a novel coil form having separable core parts adapted to clampingly engage a portion of wire in a manner to provide a cross-over portion between side by side windings when the wire is wound upon said form in accordance with the method of my invention.

Still another object of the invention is to provide a novel method and means for simultaneously winding from a single continuous length of wire two windings of a coil in side by side relation upon the same coil form.

A further object of the invention has been to provide a machine for the purpose described comprising a novel arrangement of coil form and supply spool carrying and driving instrumentalities whereby the same are driven from a single power source in such a manner that the coil form is rotated and the supply spool caused to travel in an orbit about the rotational axis of the coil form at an orbit revolution speed different from the coil form rotational speed.

Other objects, advantages, and features of the invention will appear from the following detail description of the invention taken in conjunction with the accompanying drawings, in which:

Figure 1 is a top plan view of a machine for winding wire coils and embodying my invention.

Figure 2 is a sectional view taken on the line 2—2 of Figure 1.

Figure 3 is a detail view showing more particularly one of the coil forming spools of the machine illustrated in Figure 1, and looking in the direction of line 3—3 of Figure 10.

Figure 4 is a sectional view taken about on the line 4—4 of Figure 3.

Figure 5 is a sectional view taken about on the line 5—5 of Figure 3.

Figures 6 and 7 are detail views of the locking device for locking the sections of the coil forming spool together.

Figure 8 is an enlarged detail view of one of the supply spools and a portion of the arm which carries the same, said supply spool being adapted for supplying wire for one of the windings for one of the coils adapted to be produced by the machine.

Figure 9 is a sectional view taken on the line 9—9 of Figure 2, and illustrating details of the cam operated lock means for locking the movable shaft supporting standard in place with respect to the frame of the machine.

Figure 10 is a sectional view taken substantially on the line 10—10 of Figure 2, and illustrating the manner in which a single length of

wire is associated with the supply spools and the coil forming spools, enabling the production of a coil set of the type for which the invention is designed.

Figure 11 is an enlarged partial side elevation of the machine, showing particularly one of the coil forming spools, the supply spool for supplying the wire for one of the windings of one of the coils, and the rotatable arm carrying said supply spool.

Figure 12 is an enlarged detail view of a portion of the machine, showing particularly one of the coil forming spools, this view illustrating a modification of the invention in reference to the provision of spring actuated guide fingers for guiding the wire onto the coil forming spool.

Figure 13 is a sectional view taken about on the line 13—13 of Figure 12.

Figure 14 is a sectional view taken about on the line 14—14 of Figure 12.

Figure 15 is a plan view of two oppositely wound coil units of my invention adapted to be produced by the machine herein illustrated and described, said view illustrating the general relationship of said units when employed in a motor.

Figure 16 is an edge elevation of the left hand coil unit illustrated in Figure 15, looking toward the right of said figure.

Figure 17 is a sectional view taken on the line 17—17 of Figure 15.

Figure 18 is a sectional view on the line 18—18 of Figure 15.

Figure 19 is a sectional view taken on the line 19—19 of Figure 15.

Figure 20 is an edge elevation of the right hand coil unit illustrated in Figure 15, looking toward the left of said figure.

Figure 21 is a sectional view taken on the line 21—21 of Figure 15.

Figure 22 is a sectional view taken on the line 22—22 of Figure 15.

Figure 23 is a sectional view taken on the line 23—23 of Figure 15.

Figure 24 is a sectional view similar to Figure 2, but showing certain of the parts in separated position, as when the separable portions of the coil form are separated for removal of the wound coil from the coil form.

Figure 25 is a view similar to Figure 3, but showing a coil form usable for winding a different one of the coil units of Figure 15 than that for which the coil form of Figure 3 is used, the view of Figure 25 being taken from the opposite side from that in which Figure 3 is taken, as in the direction indicated by line 25—25 of Figure 10.

Figure 26 is a view showing the right hand coil unit of Figure 15 in approximately the condition in which it is finally wound by the machine of my invention and just prior to removal of said unit from the machine, the dotted line position of the left hand coil of Figure 26 illustrating its final positioning with relation to the right hand coil of said unit.

Now for a better understanding of my invention, I will first describe the coil units produced by my invention, and for this purpose reference will be had to Figures 15 to 23 inclusive, and Figure 26.

Figure 15 illustrates two coil units, designated A and B, respectively, arranged in the general relation they will assume when emplaced in a suitable housing to form the field coils of a 4-pole electric motor, except that the coils re-

spectively generally designated by the numerals 1, 2, 3, and 4, will be angularly disposed with respect to one another. That is to say, coil 2 will usually be disposed in a plane at an angle to the plane of coil 1, and, similarly, coil 3 will be disposed in a plane at an angle to the plane of coil 2, coil 4 will usually similarly be disposed in a plane at an angle to the plane of coil 3.

Each of the coils 1, 2, 3, and 4 consists of an outer winding and an inner winding, each of the windings having an equal number of turns of wire. Referring first to coil unit A, consisting of coils 1 and 2, coil 1 comprises an outer winding 1a having a lead wire 1b; the inner turn 1c of the winding 1a is bent diagonally inwardly (Fig. 21) and its continuation forms the inner turn of the inner winding 1d. The extension 1e of the outer turn of the inner winding 1d forms a cross-over between the coils 1 and 2 which becomes the outer turn of the inner winding 2d of coil 2. The inner turn of the winding 2d is bent diagonally laterally to form a cross-over 2c, the continuation of which becomes the inner turn of the outer coil 2a. The outer turn of the winding 2a is extended to form the lead 2b. The coil unit B is formed similarly to the coil unit A except that the coil unit B is formed by winding the coils in reverse directions from that of the coil unit A. The corresponding portions of the coil unit B are designated by the reference characters 3a, 3b, 3c, 3d, and 3e, and 4a, 4b, 4c, 4d and 4e corresponding to the portions previously described in reference to coil unit A.

It will be noted that the coil unit A comprising the coils 1 and 2 with their respective outer and inner windings 1a and 1d, and 2a and 2d, is formed entirely from a single continuous length of wire beginning with the lead 1b and ending with the lead 2b. Similarly, the coil unit B comprising the coils 3 and 4, each having their respective outer and inner windings 3a and 3d, and 4a and 4d, is entirely formed of a single continuous length of wire beginning with the lead 3b and ending with the lead 4b. The coil units A and B, each made of a single continuous length of wire, eliminate the necessity for a solder connection, or other mechanical connection, between the ends of the coils 1 and 2, or 3 and 4, required to be interconnected. As will be apparent, the continuous cross-over 1e forms the electrical connection between the coils 1 and 2 of the coil unit A, and likewise the continuous cross-over 3e forms the electrical connection between the coils 3 and 4.

The machine of my invention for winding the coil units A and B, each entirely from a respective single length of wire, will now be described.

Referring first to Figures 1, 2, 10 and 11, the machine of my invention comprises a base 10 to which are suitably secured the vertical standards 11 and 12, the upper ends 11a and 12a of which form bearings for the hollow shafts 13 and 14, respectively. Coil forming spools generally designated 15 and 16 are respectively secured to the shafts 13 and 14. Gears 17 and 17' are keyed to the rear ends of the shafts 13 and 14, respectively. The gears 17 and 17' mesh with a gear 18 secured to a drive shaft 19 adapted to be driven by a suitable source of power, not shown, for rotating the hollow shafts 13 and 14.

Extending through the hollow shaft 14 is a driven shaft comprising the shaft parts 20 and 21, which shaft parts are suitably clutched together by means of the tongue 20b entering groove 21b. Extending through the hollow shaft 13 is a similar driven shaft comprising shaft parts corresponding

to the shaft parts 20 and 21, the outer shaft part 21' of which is seen in Figures 1, 10, and 11. The outer shaft parts 21 and 21' of the inner driven shafts are suitably journaled in the upper ends of standards 22 and 23, respectively, which are movably secured to the base member 10. For the latter purpose each of the standards 22 and 23 are provided with their respective foot portions 22a and 23a mounted for sliding movement in respective channels provided in the base member 10. Cam operated locking means including the cam levers 24 and 24' are respectively provided on the foot portions 22a and 23a for locking the movable standards 22 and 23 in respective adjusted positions relative to the base member 10. The cam-operated locking means for each of the standards 22 and 23 are identical and it will therefore suffice to describe one only of said means as provided on the standard 22, the details of which are shown in Figures 2 and 9. Pivotedly secured between the forked cam elements 24a and 24b, as by means of the pivot pin 25, is a clamping member 26 extending through a slot or recess in the foot member 22a, and having at its lower end an enlarged clamping element 26a located in a suitable recess 27 in the base member 10.

It will be apparent that when the cam lever 24 is moved in a clockwise direction (Figure 2) around the pivot 25, this will relieve the clamping engagement of the clamping element 26a with respect to the upper wall of the recess 27 and permit the standard 22 to be shifted lengthwise of the recess 27, engaging the nut 28 on the outer end of the shaft part 21 to unclutch shaft parts 20 and 21.

Supply spool carrying arms 29 and 30 are respectively keyed to shaft parts 21 and 21' for rotation with the respective inner driven shafts. The opposite ends of the arms 29 and 30 carry respective wire supply spools 31 and 32 which are mounted for rotation relative to their respective arms about the axis of the respective hub 31b or 32b.

The inner driven shafts for rotating supply spool carrying arms 29 and 30 are driven through suitable gearing from the same source of power which drives the hollow shafts 13 and 14. For this purpose, shaft part 20 has keyed thereto a gear 33, and the corresponding shaft part extending through the hollow shaft 13 likewise has keyed thereto a gear 34, the gears 33 and 34 meshing with a gear 35, which latter gear is keyed to the shaft 19 driven, as above mentioned, by a suitable source of power, not shown. Thus it will be apparent that the inner driven shaft comprising the shaft parts 20 and 21 when clutched together will rotate independently of the outer hollow shaft 14, though the inner and outer shafts are driven from the same source of power.

The coil forming spools 15 and 16 are respectively secured to the outer hollow shafts 13 and 14, and are separable sectional spools of identical construction, so that the description of one will serve to describe the other. Figures 3 to 7 and 11 will now be referred to.

As shown best in the above figures, the coil forming spool comprises the separable sections 15a and 15b, each having respective outer flange portions 15c and 15d which serve to confine between them the wire fed to the coil forming spool in the winding operation, and which is wound upon the intermediate hub or cord portions of said spool sections 15a and 15b. The intermediate hub portions of the coil forming spool 15 have formed therein a diagonal groove or recess 15e, a portion

of which is formed in the intermediate hub portion 15f of the hub section 15a, and a portion of which groove 15e is formed in the hub portion 15g of the spool section 15b. The spool sections 15a and 15b of coil form 15 are separable along the center of the groove 15e as indicated by the line 15x. The groove 15e extends diagonally across coil form 15 at an angle to the rotational axis of the latter.

Locking means is provided for holding the spool sections 15a and 15b together, and this locking means may comprise a pin 36 permanently connected to the spool section 15b and adapted to enter a hole provided in the spool section 15a, as seen best in Figure 3. The locking means further comprises a locking screw 37, the shank of which extends through suitable openings provided in the sections 15a and 15b of the spool 15, said screw shank being formed with a bayonet slot 37a adapted to cooperate with a pin or projection 38, so that when the shank of the locking screw is inserted through the hole in the sections 15a and 15b and rotated by means of a handle 37b, the spool sections will be locked together by cooperation of the pin 38 with the bayonet slot 37a.

The method of winding the coil unit A upon the coil winding machine of my invention will now be described, with particular reference to Figures 10, 11, and 15, and 26.

For the purpose of winding the coil unit A, the lead end 2b of the wire is led on the supply spool 31 and inserted in a notch 31a provided in the flange side of said spool. Now the spool 31 is rotated in a counterclockwise direction (Figure 10) until a sufficient length of wire has been wound about the supply spool 31 to constitute the outer winding 2a of coil 2. The additional continuous predetermined length of wire necessary to form the other three windings, including the cross-overs and end lead 1b, is now measured off and the end of this wire opposite the end which has already been secured to the supply spool 31 is severed from the initial supply source of wire and the portion 2c is clamped in groove 15e of coil form 15. Next the mid-point of the total length of wire is clamped in the clamp member 40 carried by the end of a spring 41 suspended in any suitable manner above the machine mid-way between coil forms 15 and 16. The lead end 1b of the wire is then inserted in the slot 32a provided in the flange side of the supply spool 32. Now the spool 32 is rotated in a counter-clockwise direction (Figure 10) to wind upon the supply spool 32 a length of wire sufficient to constitute the outer winding 1a of the coil 1. Next the portion 1c of the wire is clamped in the groove 15e of the coil forming spool 15.

With the wire disposed as just described, the machine is now started so as to rotate the drive shaft 19 so as to drive the gears 18 and 35 in the direction of the arrows in Figure 10. This will cause the gears 17 and 17' to rotate in the direction of the arrows (Figure 10), causing counter-clockwise rotation of the coil forming spools 15 and 16. At the same time, the gear 35 will rotate the gears 33 and 34 in the same direction as gears 17 and 17', and this will cause the arms 29 and 30 likewise to rotate in a counter-clockwise direction (Figure 10) about the axes of shafts 21 and 21', to which said arms 29 and 30 are respectively secured.

The rotation of the coil forming spools 15 and 16 serves to wind upon coil form 15 adjacent the flange portion 15d thereof the winding 1d of coil

1, the rotation of coil form 16 serving at the same time to wind upon the latter coil form adjacent the flange portion 16d thereof the winding 2d of coil 2. Simultaneously, the arms 29 and 30 are being rotated in the same direction as coil forms 15 and 16, but at twice the speed of rotation of coil forms 15 and 16, so that the arms 29 and 30 make two revolutions for one revolution of the coil forms 15 and 16. Rotation of the arm 29 in the same direction as, and about the axis of, the coil form 16 serves to pay off wire from the supply spool 31 so as to wind upon the coil form 16 adjacent the flange portion 16c thereof the winding 2a of coil 2 in side by side or face to face relation to the winding 2d of coil 2 being simultaneously wound upon coil form 16. Similarly, rotation of the arm 30 in the same direction as, and about the axis of, coil form 15 serves to pay off wire from the supply spool 32 to wind upon the coil form 15 adjacent the flange portion 15c thereof the winding 1a of coil 1 in side by side or face to face relation to the winding 1d of coil 1 being simultaneously wound upon the coil form 15.

It is notable that since the windings 1a and 1d of coil 1 are being simultaneously wound upon coil form 15 in side by side or face to face relation, and the windings 2a and 2d of coil 2 are being simultaneously wound upon coil form 16 in side by side or face to face relation, it is necessary that the arms 29 and 30 rotate at twice the speed of rotation of the coils 15 and 16, as otherwise rotation of the arms 29 and 30 would not serve to wind wire upon the coil forms 15 and 16 to provide the outer windings 1a and 2a, respectively, of the coils 1 and 2. The gearing 33, 35, and 34 is therefore designed to produce a speed of rotation of the shafts 21 and 21' which is twice the speed of rotation of the hollow shafts 13 and 14 to which the coil forms 15 and 16 are secured and which latter rotation is produced by the gearing 17, 18, 17'.

It will be apparent from the foregoing that the winding of the windings 1a and 1d of coil 1 upon coil form 15, and the winding of windings 2a and 2d of coil 2 upon coil form 16 all takes place simultaneously, so that the windings of coils 1 and 2 are completed at the same time by the operation of the machine of my invention. During the operation of the machine to wind the wire upon the coil forms 15 and 16, the portion 1e of the wire clamped by the clamp means 40 will be pulled downwardly as permitted by the suspension of the light spring 41 from which the clamp means 40 is suspended. Figure 26 illustrates the condition of the wire when the operation of the machine is completed, and shows the winding of the coil unit A in a nearly completed condition, with the mid section of the wire forming the cross-over 1e drawn down toward the machine extending from the spring 41 from which the mid section 1e of the wire is suspended.

When the machine has formed the coils 1 and 2 in the condition indicated in Figure 26, the operation of the machine is discontinued, and, prior to the removal of the coils 1 and 2 from the coil forming spools 15 and 16, small tying wires 45 may be inserted through the slots 15h in the flange portion 15d of the coil forming spool 15, and similar wires 45 may be inserted through the corresponding slots of the flange portion 16d of the coil forming spool 16, these wires 45 engaged around the coils 1 and 2 and the ends of the tying wires suitably twisted so as to hold the windings of the coils 1 and 2 in the condition indicated in Figure 26.

After the tying wires 45 have been inserted and tied around the coils 1 and 2, removal of the coils 1 and 2 from the coil forms 15 and 16 may be effected as follows: The cam lever 24 will be rotated in a clockwise direction (Figure 2) around its pivot 25, to release the clamping element 26a from clamping relation with the base member 10, so that the standard 22 may be moved to the left, referring to Figure 2. Leftward movement of the standard 22 will cause disconnection of shaft section 21 from shaft section 20 by engagement of the standard 22 with the nut 28 carried on the end of the shaft section 21. Prior to leftward movement of the standard 22, the handle 37b of the locking screw 37 will be rotated to cause the pin or projection 38 to be aligned with the longitudinally extending portion of the bayonet slot 37a under which condition the section 16a of the coil forming spool 16 may be moved leftwardly referring to Figure 2 simultaneously with the leftward movement of the standard 22 to cause separation of the sections 16a and 16b of the coil forming spool as well as separation of the shaft sections 20 and 21, so that the parts will now be in the condition of Figure 24, permitting removal of the coil wound upon the intermediate or core portions of the coil forming spool 16. In like manner, the standard 23 may be moved relative to the base 10 and the sections 15a and 15b of the coil forming spool 15 may be separated after actuation of the locking means to unlock the sections of the coil forming spool 15.

In this connection it will be noted that the bearing 60 may fairly tightly engage coil form part 16a and shaft part 21 so that when the standard 22 is moved leftwardly, after release of the locking means, the parts will assume the condition of Figure 24. For a similar reason, like movement of standard 23, after release of the locking means, may cause the corresponding parts to assume a similar condition.

When the coil forms 15 and 16 and shaft sections 20 and 21 and the corresponding shaft sections relating to arm 30 are all in the condition illustrated by Figure 24, it will be apparent that coils 1 and 2 may be removed from the machine substantially in the condition illustrated in Figure 26. Now in order to finish the coil unit A to the condition of Figure 15, it is only necessary to rotate coil 1 in counterclockwise direction (Figure 26) to the dotted line position of the latter figure, thus adding to winding 1d of coil 1 a portion of the slack wire 1e extending between coils 1 and 2. The lead 2b is then wound around winding 2a of coil 2 to place lead 2b in the dotted line position of Figure 26, thereby finishing the coil unit to the condition of Figure 15.

The coil unit B may be wound upon the machine of my invention in a manner similar to that described in reference to the winding of the coil unit A. For the purposes of winding the coil unit B, however, the sectional spools 15 and 16 will be removed from the machine when the parts are in the condition of Figure 24, and coil forming spools of the form of spool 50 illustrated in Figure 25 will be substituted for the spools 15 and 16. The coil forming spools 50 are of the same construction as spools 15 and 16 except that the groove 50e, corresponding to the grooves 15e and 16e of the coil forming spools 15 and 16, and a portion of which groove 50e is formed in each of the hub or core portions 50g and 50f of the respective spool sections 50a and 50b, extends diagonally across the hub or core sections 50f and

58g in an opposite direction from the direction in which the corresponding groove extends across the hub or core portions of the coil forming spools 15 and 16.

For the winding of coil unit B it is necessary to use the spool of the form of spool 50 with the oppositely disposed diagonal groove 50e because the windings of coils 3 and 4 of coil unit B are wound in opposite directions from the directions in which the windings of coil unit A are wound. However, for the production of coil unit B, it is only necessary to substitute the coil forming spools of the form of spool 50 for the spools 15 and 16, and to operate the machine of my invention in reverse direction from the direction in which it is operated for purposes of winding the coil unit A; that is to say, the drive shaft 19 will be rotated in the reverse direction from that above described, so as to cause gears 34 and 17, and gears 33 and 17' to be rotated in a clockwise direction, referring to Figure 10, which is in a direction opposite to the direction of the arrows indicated in Figure 10. Thus, in the operation of the machine of my invention for the winding of coil unit B, the coil forming spools 50 and the supply spool carrying arms 29 and 30 will all be rotated in a clockwise direction, referring to Figure 10. Other than as above indicated, the operation of the machine of my invention will be the same for the winding of either the coil unit A or the coil unit B.

It will be noted with regard to the winding of either the coil unit A or coil unit B that for the insertion of the portion of the wire corresponding to the portions 1c, 2c, 3c, or 4c, into the diagonal grooves 15e, 16e, or 50e of the coil forming spools, it is necessary to slightly separate the sections of said coil forming spool when the sections are unlocked and after the respective portion of the wire is positioned in the respective groove formed partially in each of the hub or core sections of respective coil forming spools, the said sections of the respective spool will be moved together so that the sides of the groove clamp the respective portion of the wire disposed therein, wherupon the spool sections are locked together by actuation of the locking member 37. In the locking actuation of the locking member 37, the sections such as 15a and 15b of the coil forming spools will be drawn together by the cooperative action of the bayonet slot 37a with the pin or projection 38, so that the portion of the wire disposed in the groove formed in the hub or core portions of the coil forming spool will be tightly clamped therein.

An additional feature of my invention is illustrated in Figures 12 to 14 inclusive, relating to means for guiding and pressing the wire into position upon the hub or core portions of the coil forming spool during the winding of the coils thereon. The use of such guiding and pressing means may be desirable or advantageous where the coils to be formed or wound in the operation of the machine of my invention utilize a very heavy wire not otherwise made readily conformable to the winding of the coil in a rectangular or other appropriate configuration, as determined by the configuration of the hub or core portions of the coil forming spools.

As shown in Figure 12 to 14, the wire guiding and pressing means comprises a plurality of spring pressed fingers, certain of which are carried by fixed parts of the machine and certain other of which fingers are carried by the rotatable supply spool carrying arms. Since Figure

12 is a view showing a portion of the machine similar to Figure 11 and the corresponding parts bear the same references, they will not be further described. In Figure 12, the standard 11 is provided with a lug 51 having an aperture in which is received the shank or stud 51a of a spring pressed finger 51b adapted to engage the wire 1d which is to constitute the inner winding of the coil 1 being wound on the coil forming spool 15. For this purpose the spring 52 normally urges the finger 51b into engagement with the wire. Extending from the upper shaft housing portion 11a of the standard 11 is another lug 53 similarly provided with an opening receiving the shank 54a of a finger 54 normally pressed by the spring 55 into engagement with the wire 1d. The supply spool carrying arm 30 is provided with lugs 56 and 57 similarly movably receiving the shanks 58a and 59a of spring pressed fingers 58 and 59 adapted to engage the wire 1a which is to constitute the outer winding of the coil wound upon the coil forming spool 15. The fingers 51b, 54, 58 operate to guide and press said wire onto the respective core portions of said spool in the operation of the machine.

From the foregoing it will be seen that the machine and method of winding the coil units of my invention are capable of performing the rather complicated operation of winding coil units each comprising two coils of opposite polarity, each coil consisting of an inner and an outer winding, all wound simultaneously from a continuous single length of wire, in a very efficient and expeditious manner. It will be noted that the coil unit wound upon the machine of my invention in accordance with the method above described has terminal leads such as 1b and 2b, and a cross-over such as 1e interconnecting the coils 1 and 2, all located in convenient positions having in mind the requirements when mounting the coils in an electric motor housing. In this connection it may be mentioned that the screw bolts employed for interconnecting the parts of the motor housing usually have to pass between the respective coils, such as 1 and 2, of a coil unit such as A, and in order to facilitate the connection of the lead terminals of the coils to the brushes or to positive and negative terminals of the motor, it is desirable and necessary that the terminal ends of the coil should be located in convenient positions for this purpose, and that the cross-over such as 1e interconnecting the coils such as 1 and 2 should be positioned so as not to interfere with the passage of the screw bolts interconnecting the housing parts of the motor unit. The winding of the coil unit upon the machine of my invention and in accordance with the method above described is admirably suited to the foregoing purpose.

It will be apparent that, in accordance with the principles of the machine and method of my invention, more than two coils, each having two side by side windings, may be wound simultaneously from a single continuous length of wire by increasing the number of sets of rotatable coil forms and arms rotatable about the rotational axes of said coil forms, which sets may be disposed intermediate the two sets specifically illustrated herein, all sets being simultaneously operated in the same coordinated relationship, the wire extending intermediate the coil forms 15 and 16 being trained over the supply spools and coil forms of the intermediate sets, and the wire 75 extending intermediate each set being clamped

11

at its mid-point by a respective clamp 40 suspended from a respective spring 41.

It will be understood that in the drawings the parts of coil forms 16 and 50 corresponding to the parts of coil form 15, designated 15a, 15b, 15c, 15d, 15e, 15f and 15g, are correspondingly designated as 16a, 16b, etc., and 50a, 50b, etc. It may be noted also that the locking means designated 36, 37, 38 and described with reference to coil form 15 is similarly incorporated in the coil forms 16 and 50 and designated by the same reference characters on the drawings.

In the threading of the wire onto the machine, and before the latter is started into operation, an extra turn or portion of a turn of wire may be wound on one of the coil forms 15 or 16 to constitute a portion of the inner winding of one of the coils of the coil unit being wound on the machine, in order to compensate for extra wire added to the corresponding winding of the other coil of said coil unit in the finishing operation which is accomplished after the coils are removed from the machine in a condition similar to that illustrated by Figure 26.

During the winding of the coil unit on the machine of my invention, the mid-point of the wire is yieldably suspended, as above mentioned, preferably under a constant tension. For this purpose the spring 41 is secured to a cable 61 trained over pulleys 62 and 63 rotatably mounted above the machine in any suitable manner. To the other end of the cable 61 is attached a weight 64. Thus the degree of tension on the wire will be the same, or constant, throughout the winding operation.

Having thus described my invention, what I claim as new and desire to secure by Letters Patent of the United States, is:

1. In a machine of the class described, in combination, a pair of rotatable coil forms, a member rotatable in an orbit about the axis of rotation of one of said coil forms, a second member rotatable in an orbit about the axis of rotation of the other coil form, a respective spool rotatably carried by each respective member aforesaid, said spools being adapted to carry portions of a continuous length of wire, and said coil forms having means to clamp respective portions of said wire, means for rotating said coil forms in the same rotational direction, and means for rotating said members in the same rotational direction as the coil forms.

2. In a machine of the class described, in combination, a pair of rotatable coil forms, a member rotatable in an orbit about the axis of rotation of one of said coil forms, a second member rotatable in an orbit about the axis of rotation of the other coil form, a respective spool rotatably carried by each respective member aforesaid, said spools being adapted to carry portions of a continuous length of wire, and said coil forms having means to clamp respective portions of said wire, means for resiliently suspending a portion of the wire intermediate said coil forms, means for rotating said coil forms in the same rotational direction, and means for rotating said members in the same rotational direction as the coil forms.

3. In a machine of the class described, in combination, a rotatable coil form, a member rotatable in an orbit about the axis of rotation of said coil form, a spool carrying a coil of wire and rotatably carried by said member, said coil form having means for clamping a portion of the wire carried by said spool, means for yieldably suspending a portion of said wire extending from said

12

spool, means for rotating said coil form, and means for rotating said member in the same rotational direction as the coil form.

4. The method of winding a coil which comprises winding one end of a predetermined length of wire upon a spool, securing a portion of said length of wire intermediate its ends to a coil form, resiliently suspending a portion of said length of wire extending from said coil form to wind the latter portion of wire thereon, rotating said coil form, and moving said spool in an orbit about the axis of rotation of said coil form to wind the wire from the spool onto the coil form.

5. The method of winding a coil which comprises winding one end of a predetermined length of wire upon a spool, securing a portion of said length of wire intermediate its ends to a coil form so that the portion of wire so secured extends across said coil form at an angle to the rotational axis thereof, resiliently suspending a portion of said length of wire extending from said coil form to wind the latter portion of wire thereon, rotating said coil form, and moving said spool in an orbit about the axis of rotation of said coil form to wind the wire from the spool onto the coil form.

6. The method of winding a coil which comprises winding one end of a predetermined length of wire upon a spool, securing a portion of said length of wire to a coil form so as to extend across the latter at an angle to the rotational axis thereof, resiliently and yieldably suspending a portion of said length of wire extending from said coil form, rotating said coil form to wind the latter portion of wire thereon, and moving said spool in an orbit about the axis of rotation of said coil form in the same rotational direction as that of said coil form and at an orbit revolution speed twice the rotational speed of the coil form to wind the wire from the spool onto the coil form.

7. The method of winding a coil which comprises winding one end of a predetermined length of wire upon a spool, winding the opposite end of said wire upon a second spool, securing a portion of said wire adjacent the first spool to a coil form, securing a portion of said wire adjacent the second spool to a second coil form, rotating said coil forms, and moving said spools in respective orbits about the axes of rotation of said coil forms.

8. The method of winding a coil which comprises winding one end of a predetermined length of wire upon a spool, winding the opposite end of said wire upon a second spool, securing a portion of said wire adjacent the first spool to a coil form so as to extend across said coil form at an angle to the rotational axis thereof, securing a portion of said wire adjacent the second spool to a second coil form so as to extend across the latter coil form at an angle to the rotational axis thereof, resiliently suspending the wire intermediate said coil forms, rotating said coil forms in the same direction at the same speeds, and moving said spools in respective orbits about the axes of rotation of said coil forms in the same rotational direction as said coil forms, and at an orbit revolution speed twice the rotational speed of said coil forms.

9. A machine as claimed in claim 3, wherein the coil form comprises separable core portions.

10. A machine as claimed in claim 3, wherein the coil form comprises separable core portions, and locking means for detachably connecting said core portions in integral relation.

11. A machine as claimed in claim 3, wherein

the coil form comprises separable core portions, and locking means for detachably connecting said core portions in integral relation, said core portions having meeting recessed edges to provide a wire receiving groove adapted to clamp wire disposed therein when said edges of said core portions are disposed in meeting relation.

12. A machine as claimed in claim 3, wherein said first means comprises a groove formed in said coil form and diagonally extending across the same at an angle to the rotational axis thereof.

13. A machine as claimed in claim 3, wherein said first means comprises a groove formed in said coil form and diagonally extending across the same at an angle to the rotational axis thereof, and means for rotating said coil form and said member in the same rotational direction at different respective rotational speeds.

14. A machine as claimed in claim 1, wherein said first means comprises a groove formed in each respective coil form and extending diagonally across the same at an angle to the rotational axis thereof.

15. A machine as claimed in claim 1, wherein said first means comprises a groove formed in each respective coil form and extending diagonally across the same at an angle to the rotational axis thereof, and said rotating means effecting a rotational speed of said members different from the rotational speed of said coil forms, and means for tensionally suspending a portion of said wire intermediate said coil forms.

16. In a machine of the class described, in combination, a rotatable shaft, a coil form secured thereto for rotation therewith, a second shaft rotatable coaxially with the first shaft and comprising separable shaft parts, and means for detachably interconnecting said parts, a member secured to one of said shaft parts for rotation therewith, a spool carrying a coil of wire and rotatably carried by said member, said coil form comprising core portions, means for moving one of said shaft parts axially relative to the other for detachment therefrom, and means on the axially movable shaft part engageable with one of said core portions for separating the same from the other core portion.

17. In a machine of the class described, in combination, a pair of rotatable coil forms, a member rotatable in an orbit about the axis of rotation of one of said coil forms, a second member rotatable in an orbit about the axis of rotation of the other coil form, a respective spool rotatably carried by each respective member aforesaid, said spools being adapted to carry portions of a continuous length of wire, and said coil forms having means to clamp respective portions of said wire, means for rotating said coil forms in the same rotational direction, and means for rotating said members in the same rotational direction as the coil forms and at twice the rotational speed of said coil forms.

18. In a machine of the class described, in combination, a pair of rotatable coil forms, a member rotatable in an orbit about the axis of rotation of one of said coil forms, a second member rotatable in an orbit about the axis of rotation of the other coil form, a respective spool rotatably carried by each respective member aforesaid, said spools being adapted to carry portions of a continuous length of wire, and said coil forms having means to clamp respective portions of said wire, means for resiliently suspending a portion of the wire intermediate said coil forms, means for rotating said coil forms in the same rotational direction, and means for rotating said members in the same rotational direction as the coil forms and at twice the rotational speed of said coil forms.

19. In a machine of the class described, in combination, a pair of rotatable coil forms, a member rotatable in an orbit about the axis of rotation of one of said coil forms, a second member rotatable in an orbit about the axis of rotation of the other coil form, a respective spool rotatably carried by each respective member aforesaid, said spools being adapted to carry portions of a continuous length of wire, and said coil forms having means to clamp respective portions of said wire, means for resiliently suspending a portion of the wire intermediate said coil forms, means for rotating said coil forms in the same rotational direction, and means for rotating said members in the same rotational direction as the coil forms and at twice the rotational speed of said coil forms.

20. In a machine of the class described, in combination, a rotatable coil form, a member rotatable in an orbit about the axis of rotation of said coil form and in the plane thereof, a spool carrying a coil of wire and rotatably carried by said member, said coil form having means for clamping a portion of the wire carried by said spool, means for yieldably suspending a portion of said wire extending from said spool, means for rotating said coil form, and means for rotating said member in the same rotational direction as the coil form.
